REACTOR SUPPORTS

Daniel B. Banks, Drexel Hill, Pa., assignor to Sun Oil Company, Philadelphia, Pa., a corporation of New Jersey

Application April 22, 1954, Serial No. 425,014

5 Claims. (Cl. 248—128)

This invention relates to the class of apparatus employed in the chemical and petroleum industries for high temperature operations termed reactors, and more particularly to support means for such devices.

With the introduction of processes requiring high temperatures, the contraction and expansion of the supported apparatus and its connecting piping requires special consideration due to the weight and size of the elements. While known metals are used, making it possible to anticipate the thermal response of the various elements under assumed conditions, actual operation requires a form of construction allowing for all possible variations of natural phenomena without interrupting the process. One solution fixes the large important equipment assemblies and absorbs the movement requirements in the connecting elements, often especially designed. In other instances the connectors remain relatively fixed, while the large assemblies are required to adjust. It is the object of this invention to provide improved construction in the field of movable assemblies and the combination of parts to permit absorption of temperature effects within wide limits.

The improved construction comprises a support on which the reactor assembly rests. Supporting surfaces adapted to reduce the bearing contact to a minimum extend from the assembly body in predetermined directions relative to the fixed connectors. The fixed connectors and the supporting bearings are positioned in substantially the same horizontal plane, thereby eliminating all vertical couples tending to change the axial center or actual plumb position of the reactor during operation. The result of thermal response in the fixed connectors is to move the assembly on the directioned bearing surfaces, easing the stress and insuring the maximum efficiency in working conditions. To insure uninterrupted operation and in addition to the planetary construction noted, the major movement in the selected horizontal plane is directioned by guide elements cooperating with one of the supports, and the tolerances in the guided movement are absorbed by point bearings engaging the bearing surfaces of the remaining supports. This is particularly effective where there are several fixed connectors expanding and contracting under conditions of different or unequal stress tending to horizontally move the reactor in several directions simultaneously.

These principles of construction and operation are illustrated by a reactor used in petroleum refining as one form of application. For a better understanding of the invention, reference may be had to the accompanying drawings and the description which is directed to this particular form of embodiment.

Figure 1 is an elevational view of the supporting elements.

Figure 2 is a sectional plan view of the construction shown in Figure 1 taken on line 2—2.

Figure 3 is a sectional plan view of the bearing means taken on line 3—3 of Figure 4.

2

Figure 4 is a sectional elevational view of the element taken on line 4—4 of Figure 3.

In Figure 1, the upper or suspending portion of a typical reactor 10 is shown engaging the support structure 12. 5 This figure is limited to the pertinent section of the structure and the elements of support necessary to describe the invention. The structure 12 includes an economical arrangement of vertical and horizontal steel members which position the bearing elements in support of the reactor 10.

Bearing means 14, 15 and 16, spaced at the circumferential third points around the reactor 10, are supported by horizontal members 17 fabricated to engage the vertical steel legs 18. A flanged portion 20 of the members 15 17 presents a level, flat surface on which the bearing means 14 are placed. Outwardly projecting supports 22, 23 and 24 form one means of suspending the reactor 10 in the structure 12 and may be connected to the reactor as by the bands 26 and 27. The supports 22, 23 and 24 20 are spaced to engage the bearing means 14 at the circumferential third points and are positioned relative to the effective forces acting on the reactor. Guides 28 and 29 are fastened to the flange surface 20 to limit the movement of support 22 in a predetermined direction selected 25 to minimize operating stresses on the equipment as a whole.

To complete the general description of the assembly selected to demonstrate the construction under discussion, the structure 12 is shown extending above the reactor 10 30 to support the member 30. This forms an operating surface for specific purposes not connected with the supporting details previously disclosed and as it forms no part of the present invention will not be further discussed. A manhead or service opening 32 is shown on the top of 35 the reactor enclosed by a cover 34. Such a covered opening may be used as a means for placing reacting materials inside the reactor 10 or for an inspection opening, or both. In addition, two pipe openings 40 and 42 are shown connecting the reactor 10 to the inlet and outlet lines 44 40 and 46 respectively. These pipe openings, limited to two for the purposes of this specification, illustrate an effective use of the bearing structure and will be thus described later when disclosing the operating characteristics of the combination. The elevation of these openings and their 45 cooperating inlet and outlet lines 44 and 46 are positioned to determine the effective horizontal plane of operation relative to the bearings 14, 15 and 16. The center lines of these pipes and connections are substantially coincident with the bearing surfaces. It will be evident, however, 50 that the disclosed principles, with slight modification of the structural details, are applicable to a wide range of similar devices.

Returning to the reactor 10, reference to Figures 1 and 2 shows three openings in the vessel. It is indicated above that any tendency of the reactor 10 to twist 55 about the vertical axis in the support 12 is substantially overcome by the use of guides 28 and 29 positioned on each side of bearing 14, thus selecting a primary direction of movement relative to the effective forces. The bearing means 14, 15 and 16 with cooperating supports 60 are positioned, further, to take advantage of this pre-selected direction of movement both horizontally and vertically. Additionally, guides 41 and 43 are placed to further directionally govern the movement received 65 from the expansion and contraction of pipe 44 and is aligned by the abutting fins 45 and 47 attached to the connection 40.

As disclosed above, the reactor 10 is supported in a tower-like structure 12 on the supports 22, 23 and 24, 70 which form a part of the bearing means generally indicated by the numbers 14, 15 and 16. Located as shown

on Figures 1 and 2, described above, further details of these bearing means are shown in Figures 3 and 4. The three points of suspension designated as bearing means 14, 15 and 16 are structurally identical in this circumstance. Consequently one bearing means only will be described as indicative of this uniform structure.

Beginning with the horizontal member 20 on which the bearing means 14 is mounted as the selected means to be described, a typical structure is shown in elevation in Figure 4. A lower alignment plate 50 rests on the upper surface of flanged portion 20 of member 17. The housing base 52 is vertically spaced from lower plate 50 by the spacer 54 inserted for construction and maintenance purposes together permitting necessary vertical adjustment. This assembly of the three elements 50, 52 and 54 is held in operating engagement by fastener elements such as the bolts 56 and 58 which pass through the flange 20. Opening 62 is let into the body 64 of the housing 66 through the base 52 as shown for the admission and removal of protective materials and is stoppered by a valved conduit assembly 70 fitted into opening 62.

As shown in the several figures of the drawing, the valved conduit assembly 70 is positioned to receive a protective material such as polysiloxanes, better known in the trade as silicones. Normally a cap 72, elevationally positioned to determine the protective material level, covers the vertical conduit 74 to prevent the entrance of the natural elements and a stop cock 76 retains or drains the viscous liquid. A T fitting 78 directs the silicones through the transverse connector 80 into and from the body 64 of the housing 66.

Within the housing 66, the lower bearing plate 68 is held in fixed position on the housing base 52 by the bolts 82 and 84 (Figures 3 and 4) and supports the bearing ball 86 and the retaining ring 88 in operating position. The upper bearing plate 90, held in position by bolts such as 92 passing through to engage the upper alignment plate 94, projects downwardly into operating engagement with the bearing ball 86. The contact surface between bearing plate 90 and bearing ball 86 is substantially at an elevation equal to the center of the forces affecting the structure, reducing to zero any force couples arising because of differences in elevation.

As shown the under side of the support 22 rests directly on the upper alignment plate 94. Below the alignment plate 94, a rain hood 96, fastened to the alignment plate 94, extends beyond the limits of the housing 66 sufficiently to permit movement of the support 22 with its attendant elements 90 and 94 on the bearing ball 86 to the necessary extreme positions. The supply of protective coating material noted above as a silicone is indicated by the numeral 98 and covers the bearing ball 86 and the retaining ring 88 up to and including the lower portion of the downwardly projecting upper bearing plate 90. The rain hood 96 keeps rain and snow out, preventing obstruction by freezing, and bars easy entrance of insects and small animals and birds as well. An inspection door 100 is let into one side of the housing 66, as indicated on Figure 3, which acts as a retainer for the protecting silicones, and also facilitates inspection of the housing 64 and bearing ball 86 as required, from time to time.

The inlet and outlet lines 44 and 46 respectively, shown in Figures 1 and 2, indicate the means for transferring fluids to and from the vessel 10, here illustrated as a reactor. As noted above they connect with the reactor in the horizontal plate of the bearing means. The considered processes of chemical and petroleum manufacture require these lines to simultaneously carry fluids at different temperatures. Under these conditions, stress differences exist in these lines exerting varying forces due to changes in the effective temperatures and the resultant expansion and contraction. These varying forces in the feed and outlet lines exert an uneven stress in the reactor 10 causing it to move on the supporting

structure. It will be evident that to maintain the reactor 10 in a fixed position would cause the fixed feed and outlet lines to rupture or shear. To insert jointed couplings between the lines and the reactor, or in the lines themselves, would reduce the operating effectiveness of the arrangement especially under conditions of high pressure which normally accompanies such high temperature effects.

In the illustrated example, the spaced supports, placed in cooperating horizontal relation with the feed and outlet line connections 40 and 42, maintain the reactor 10 in operating position. As will be evident to those versed in the art, operating position here means that the vessel 10 remains in the vertical or initial operating position, and, under the definition of this specification, is horizontally moved by thermal forces to prevent connected pipe line rupture. The guides 28 and 29 directing bearing means 14, assisted by guides 41 and 43 controlling the direction of movement of connection 40, cause the primary movement on the bearings to be in direct response to the greater force transmitted by pipe 44. Pipe 46, however, also exerts a force depending on the temperature effect and design of the outlet line which is offset to some degree by the above mentioned guides. But within the limits of the construction tolerances the sole movement of the reactor will not be as directed but tend to rotate slightly about its longitudinal axis. This movement is permitted, without binding, by the additional bearings 15 and 16 which are unguided and present a single-point bearing surface. A further advantage of this structure in which all bearings are point supports and limited to three, spaced as disclosed, is to support the reactor satisfactorily with a minimum of required alignment accuracy not afforded by any other type of bearing support. Thus the objects of the mechanism are attained through improved construction of the supporting elements and the positioning of the parts as an improved operating combination.

It will be understood that the inventor contemplates changes such as modification in the number and position of the force sources as well as in the position of the bearing supports relative thereto, and believes such to be within the spirit of this invention, as well as the substitution of the responsive vessel for one other than the reactor of the example. The spirit of the invention is believed to rest in the vessel suspension as supported by a plurality of single balled bearings of especial construction disposed and guided as discussed and should be limited only by the claims incorporated herein.

What is claimed is:

1. In combination with a reaction vessel vertically positioned in a rigid supporting structure and connected with fluid conductors entering the vessel at ninety degrees to each other and axially on the same vertical plane, flexible support means comprising a first bearing member extending from the vessel to engage bearing means on the supporting structure diametrically opposite and in the vertical plane of the axis of a first fluid conductor subjected to the greatest fluctuation in thermally created displacement, guides attached to the rigid structure on each side of the first fluid conductor and the opposing bearing member to limit the resulting vessel movement, and two additional bearing members spaced one hundred and twenty degrees from said first bearing member and in said vertical plane of the fluid conductors engaging bearing means on the rigid structure and adapted to adjust the position of the vessel for the effect of the thermally created forces in the second fluid conductor.

2. The combination of claim 1 further characterized in that each of the bearing means supporting the vessel attached bearing members include a housing mounted on the rigid support structure at the selected elevation and adapted to contain a protective coating material, a single ball bearing in said housing submerged in said coating material, retaining means in said housing holding

the ball bearing in operating position to receive the bearing member, and a cover for the housing attached to the bearing member and extending over the housing sufficiently to cover the same for all operating positions.

3. Means for supporting a vessel subjected to movement resulting from thermal effect on operating connections which comprises, in combination with a fixed supporting frame, a vessel, supporting connectors secured to and equidistant from the vertical axis of the vessel, a plurality of separate ball bearings spaced to cooperate with the supporting connectors, separate housings mounted on the supporting frame at the same vertical height and enclosing each of said ball bearings in spaced relation, means supporting said connectors and affording bearing surfaces to contact said ball bearings in sliding engagement, and means secured to the frame for admission to the housings enclosing each ball bearing of a protective liquid in which the ball is immersed.

4. The construction defined in claim 3 including a cover over each of the housings enclosing the separate bearing balls, said cover being in fixed position relative to the corresponding vessel-supporting connector.

5. Means for supporting a vessel subjected to movement resulting from thermal effect on operating connections which comprises, in combination with a fixed sup-

10

15

25

porting frame, a vessel; a first pipe connection secured to the vessel for flow of fluid therebetween; supporting connectors secured to and equidistant from the vertical axis of the vessel; bearings carried by the frame, located in substantially the same horizontal plane as the pipe connection, circumferentially spaced to cooperate with the supporting connectors, said supporting connectors and bearings being positioned to locate one of said bearings diametrically opposite said first pipe connection; and a second pipe connection secured to the vessel located between the first pipe connection and the bearing located substantially opposite thereto; the other bearings, two in number, located, circumferentially, on opposite sides of the first named pipe connection, one of said two bearings being located, circumferentially, between the two pipe connections.
